UNITED STATES PATENT OFFICE.

CHARLES KOEHLER, OF CHICAGO, ILLINOIS.

PIANO ACTION.

Application filed July 9, 1923. Serial No. 650,380.

To all whom it may concern:

Be it known that I, CHARLES KOEHLER, a citizen of the United States, residing at Chicago, in the county of Cook and State of Illinois, have invented certain new and useful Improvements in Piano Actions, of which the following is a specification.

This invention has to do with certain improvements in piano actions—that is, the mechanism for transferring the movement of the finger key of the piano to the hammer or striker.

One object of the invention is to provide an arrangement whereby the movement of the key is transferred to the hammer by an arrangement of parts which eliminates the necessity of using expensive materials such as buck-skin or specially prepared leather on the surfaces of certain of the parts which come into contact. In this connection, it has been customary in the past to face certain of the parts with leather of suitable nature, so that the proper action will be given both during the operation of transferring movement to the hammer and the further operation of disengaging the parts so that the hammer will strike freely. This leather, so used in the past, is expensive and requires great care and skill in placing it on the parts so as to secure the proper action.

According to the present invention I have provided an arrangement whereby the movement is transmitted between the parts by the use of silken cords or bands and without the necessity of using this specially characterized leather. At the same time I have provided an arrangement whereby the action itself is very greatly improved and whereby the cost of construction is considerably lowered and the touch made much lighter.

A further feature of the invention relates to the provision of an improved means whereby the action may be very easily adjusted so as to secure proper striking of the hammer with the desired lightness of touch. According to this feature of the present invention, the exact position of the hammer at which the same is disengaged from the key lever may be easily adjusted so as to ensure accurate hammer movement combined with lightness of touch and proper recoil.

A further object of the invention is to combine all of the foregoing features in an arrangement of simple construction and great durability and which can be cheaply manufactured and assembled.

Other objects and uses of the invention will appear from a detailed description of the same which consists in the features of construction and combinations of parts hereinafter described and claimed.

In the drawing:

Fig. 1 shows a vertical elevation of a piano action embodying the features of the present invention, the same being shown in the position which the parts occupy with respect to the piano frame when the hammer is at rest, the finger key being broken away so as to shorten up the figure;

Fig. 2 shows a perspective view of the butt on the lower end of the hammer stem; and

Fig. 3 shows a perspective view of the upper portion of the operating trigger together with the cord which engages the aforesaid hammer butt.

In the construction illustrated in the drawing, the finger key is designated by the numeral 4. It is pivoted to the frame bar 5 on the pin 6, and the rear end of the key lever 4 normally stands at rest against a cushion of felt or the like 7 on the top surface of a frame bar 8. A pressure block 9 is threaded upon the upper end of a stem 10 on the rear end of the key lever 4 so that said pressure block can be raised and lowered for purposes of adjustment.

The cord or string is designated by the numeral 11. The hammer 12 is made of felt or other appropriate material and is carried on the upper end of the hammer stem 13. Normally the hammer stem 13 rests against a felt or cushion facing 14 on the frame bar 15 as shown in Fig. 1.

The lower end of the hammer stem 13 is mounted within a hammer butt 16 pivoted on the pin 17 which passes through a loop of metal strap 18 secured to the frame bar 19. The arrangement is such that the hammer butt 16 may oscillate perfectly free on the pivotal point 17.

A wippen 20 has its rear end articulated on the pivot point 21 carried by the bracket 22 which reaches down from the frame bar 19. The lower portion of the wippen 20 is preferably provided with a cushion surface composed of a pair of blocks of cushioning material 23 and 24, such as felt, located in position to receive pressure from the stem block 9 of the key lever 4. The cushioning block 23 is preferably set into a recess in the lower surface of the wippen 20, and the cush-

ioning block 24 preferably overlies and reaches beyond the limits of the block 23, as shown in Fig. 1. This arrangement ensures a double thickness of cushioning material in 5 position to receive the pressure from the block 9 and also fully protects the cushioning block 23 at its ends, as well as in its central portion.

10 A jack 25 has its lower end pivoted at the point 26 to a bracket 27 which reaches upwardly from the wippen 20. This jack 25 is preferably of bell crank shape, as shown in Fig. 1, and a spring 28 is provided between the under surface of the short arm 29 15 of said bell crank and the top surface of the wippen 20. This spring, therefore, tends to tilt the jack rearwardly so as to carry its upper portion 30 towards the hammer butt 16.

20 The hammer butt itself is preferably recessed in its lower front corners, as shown at 31 in Fig. 2, so as to establish a relatively narrow vertically extending forwardly reaching tongue 32, as clearly shown in said 25 figure. This tongue is in turn slotted inwardly as shown at 33, said slot extending in a direction substantially at right angles to the line of thrust of the jack 25 when the wippen 20 is raised. The forward corner 34 of the tongue 32 is made relatively sharp at the upper surface of the slot 33.

30 The upper portion 30 of the jack 25 is bifurcated as shown at 35 in Fig. 3 so as to establish the fingers 36 and 37 which are of 35 sufficient separation to receive the tongue between them. Also the depth of the bifurcated portion is sufficient to cause the body portion of the jack to clear the tongue at all times.

40 Stretched between the upper ends of the fingers 36 and 37 is a cord 38 of suitable material of proper size to work easily within the slot 33 of the tongue. This cord 38 may be of any suitable material, but experience 45 shows that silk is admirably adapted for use in the present invention, and I, therefore, prefer to use the same. As a matter of convenience in construction, I prefer to form a transverse slot 39 across the front face of the upper portion 30 of the jack 25, so that the ends of the cord 38 can be carried down 50 at the sides of the fingers 36 and 37 and interposed into said slot 39 and there held in place as by means of glue or the like 40.

55 Located above the heel portion 29 of the jack is a frame bar 41 into which is threaded a stem 42, the lower end of which carries a block 43 preferably faced with felt or the like 44 on its bottom surface. This block 43 can be raised and lowered in a very simple 60 manner according to this construction.

65 The hammer butt 16 carries a forwardly projecting stem 45 on the end of which is a block 46 preferably faced with felt or the like 47. A recoil block 48 is carried by the

upper end of a stem 49 on the end portion of the wippen 20, said recoil block 48 being preferably surfaced with felt or the like 50 in position to contact against the felt surface 47 of the block 46.

70 The block 46 has a finger 51 on its lower end which is preferably surfaced with a block of felt or the like 52, and the upper portion 30 of the jack 25 is preferably provided with a cushioning block 53 of felt or the like in position to engage the block 52 just above referred to. The parts are 75 preferably so arranged that the block 53 overlies the slot 39 in the upper portion of the jack 25.

80 The operation of this device is as follows: Upon quickly depressing a key lever 4, its rear end will rise so as to move the wippen 20 upwardly. The jack 25 will thus be forced up and the cord 38 will act upon the tongue of the hammer butt 16 so as to commence the striking movement of the hammer. The engagement of the cord 38 with the tongue 32 will continue until the heel 29 85 engages the knock off surface 44 of the block 43 on the stem 42 and the position of such engagement can be readily adjusted by threading the stem up or down.

90 As soon as the heel 29 engages the stop just referred to, any further rise of the wippen 20 will not only continue to throw the hammer towards the string 11, but will cause the jack 25 to swing away from the block 16, so that the cord 38 will very quickly 95 ride from under the corner 34 of the tongue 32. Instantly that this takes place, the arm and jack are completely disengaged, and the further throw of the hammer is dependent entirely upon its previously acquired 100 momentum.

105 Further rise of the wippen 20 carries the recoil block 48 towards the hammer butt 16 and into position to receive impact from the block 46 which extends rearwardly from the hammer butt 16. Consequently the recoil block 48 stands in position to take the recoil of the hammer and cushion same as soon as the hammer flies back from the string 11. The forward movement of the wippen 20 and associated parts is limited by engagement of the stem 49 with the frame bar 41. 110

115 As the wippen 20 drops downwardly the cord 38 of the jack 25 will be caused to hook into the slot 33 and catch the tongue 32 so as to lock the hammer butt 16 against rebound, thus avoiding a second stroke on the string 11 in case of a very violent depression of the key lever. In this way the action is made perfect even in the case of violent 120 striking of the finger piece and for loud playing.

125 While I have herein shown and described only a single embodiment of the features of my invention, still I do not limit myself to the same except as I may do so in the claims. 130

I claim:

1. A piano action comprising in combination a hammer, a hammer stem therefor, a hammer butt, a pivotal mounting therefor, 5 the lower portion of said hammer butt having a relatively narrow tongue, a wippen pivoted beneath the position of the hammer butt, a jack pivoted to said wippen and having its upper end bifurcated and adapted to receive the tongue of the hammer butt, there being an inwardly reaching slot in said tongue, a cord between the bifurcations of the jack adapted to engage said slot, a side- 10 wise projecting heel on the jack, a stop on said heel for limiting its upward movement, and means for adjusting the elevation of said stop with respect to the wippen substantially as described.
2. A piano action comprising in combination a hammer butt, a hammer connected thereto, a pivotal mounting for the hammer butt, a relatively narrow tongue on the hammer butt, there being an inwardly reaching slot in said tongue, a wippen pivoted be- 15 neath the position of the hammer butt, a jack pivotally mounted upon said wippen, the upper portion of said jack being bifurcated, a cord extending between the bifurcations and adapted to engage the slot of 20 the tongue, there being a sidewise project- 25 ing heel on the tongue, and means for limiting the upward movement of said heel, substantially as described.
3. In a piano action, the combination of a hammer butt, a pivotal mounting therefor, 30 an inwardly reaching transverse slot in said hammer butt, a wippen pivoted beneath the position of the hammer butt, a jack pivotally mounted upon said wippen, the upper portion of said jack being bifurcated, a cord 35 extending between the bifurcations of the jack and adapted to engage the slot of the hammer butt, and means for causing the jack to swing away from the hammer butt at a predetermined position in its upward 40 movement, substantially as described.
4. In a piano action, the combination of a hammer butt, a pivotal mounting therefor, there being a transverse inwardly extending 45 slot in the hammer butt, a jack having its upper portion bifurcated, a cord extending between the bifurcations of the jack, a pivotal mounting for the jack, means for moving said pivotal mounting vertically, and means for swinging the jack on its pivotal 50 mounting when said pivotal mounting reaches a predetermined elevation, substantially as described.

CHARLES KOEHLER.
